UNITED STATES PATENT OFFICE.

JAMES H. RAND, OF NORTH TONAWANDA, NEW YORK.

CARD INDEX.

Application filed June 11, 1921. Serial No. 476,733.

To all whom it may concern:

Be it known that I, JAMES H. RAND, citizen of the United States of America, and resident of North Tonawanda, in the county of Niagara and State of New York, have invented new and useful Improvements in Card Indexes, of which the following is a specification.

This invention relates to card indexes of the so-called visible index type wherein a series of overlapping cards are supported in a frame in spaced relation with their margins exposed, and consists in the novel features of construction and operation hereinafter described and particularly pointed out in the claims.

In the accompanying drawings which illustrate certain embodiments of the invention,—

20 Figure 1 is a front view, partly broken away, showing part of an index containing the invention;

Figure 2 is a longitudinal section on line 2—2 of Fig. 1;

25 Figure 3 is a cross section of the frame on line 3—3 of Fig. 1; and

Figure 4 is a similar cross section illustrating a modification of the frame.

Referring to Figs. 1 to 3, the frame, which is preferably made of sheet metal, comprises a flat back 5, the side margins of which are bent or folded forwardly and then inwardly as shown, and terminate in the inwardly extending flanges 6, forming with the frame back 5 a pair of opposed channels 7, 7 extending lengthwise of the frame.

Alongside of each channel 7 and parallel thereto, a second inwardly facing channel 8 is formed in front of channel 7 by a second inwardly extending flange 9 parallel to and spaced from flange 6. In the preferred construction the flange 9 is the front flange of a strip of angle or channel metal, whose rear flange 10 is welded, soldered, or otherwise secured to the rear side of the frame back 5, with the connecting web 11 lying close against the side edge of the frame.

The outer flange 9 is preferably narrower than the inner flange 6 for the reason hereinafter explained.

Mounted in the frame in overlapped, spaced relation, are a series of cards 12, each having a pair of laterally projecting

members 13, 13 adjacent its lower edge, 55 and a pair of laterally projecting members 14, 14 adjacent its upper edge. The width of the body of the card should not exceed the distance between the opposed flanges 6, 6, as the body of the card lies between the flanges 6 in a plane intersecting the plane of the flanges 6. As herein shown the projections 13 are the ends of strips 13^a, made of cardboard or the like cemented to the rear side of the lower margin of the card, 65 and the projections 14 are integral ears or tabs cut from the same sheet as the card. The strips 13^a constitute spacing means by which the overlapped cards are held in spaced relation with their opposite margins 70 projecting one beyond another to display indexing inscriptions. It will be understood however that the particular form of lateral projections at the upper and lower edges, and the particular form of spacing 75 means are not important, and that any well known or preferred form of projections and spacing means may be employed.

One pair of lateral projections, preferably the lower pair 13, 13 of each card, 80 extend into the inner pair of opposed channels 7, 7, of the frame, and the other pair 14, 14 extend into the outer pair of opposed channels 8, 8. When thus mounted, as shown in Figs. 1 and 2, the cards will slide 85 lengthwise in the frame, their top edges being guided by the front channels 8 and their bottom edges being guided by the rear channels 7. The frame should not be quite filled with cards, but an empty space should 90 be left in assembling the parts, preferably at the top end of the frame, about equal to the vertical length of a card, so that to inspect or make entries on any card, that card (and all cards above it) may be slid 95 vertically in the frame until its face is exposed. The assembling of the cards in the frame is facilitated by having the outer flange 9 narrower than the dividing wall 6 between the two channels, since in practice 10 the lower projections 13 may first be inserted in the inner channels 7, 7 by bending or springing the card to contract its lower edge in width, after which the upper edge is similarly bent or sprung to a less degree 11 and only sufficiently to insert the upper projections 14, 14 in the front channels 8, 8 but not far enough to permit them to enter the

inner channels 7, 7. The wider dividing flanges 6, 6, aid in guiding the projections 14, 14 into the outer or front channels, and minimize the chance of slipping them accidentally into the wrong channels.

It will be understood that the lower pairs of projections might be inserted in the front channels and the upper pair in the rear channels; or that the series of cards could be reversed top for bottom in which case the exposed projecting margins for displaying the indexing would appear at the lower edges of the cards instead of the upper edges. In either event the operation of the device would be essentially the same, but I prefer the arrangement shown both on the score of convenience and appearance.

In Fig. 4 I have illustrated one of a number of alternative structures which might be used for producing a frame with the two parallel inwardly facing channels at each side of the frame. In this form the entire frame structure is made of an integral piece of sheet metal. Each side margin of the frame back 5 is bent forwardly and then inwardly to form the inner channel 7, thence is bent back upon itself forming a two-ply dividing flange 6*, and thence is bent again forwardly and inwardly to form the front channel 8, the front flange 9*, as before, being narrower than the rear or dividing flange 6* between the two channels.

An index constructed as above described will hold the cards flatwise in the frame, as contrasted with indexes of the overlapping card type having hinged or swinging cards free at one edge, thus rendering the device more flat and compact, and diminishing the danger of breaking or mutilating the cards, while at the same time permitting the cards to be freely manipulated for inspecting them or making entries on them by sliding them lengthwise in the frame.

I claim:

1. An index comprising a frame having two parallel inwardly facing channels at each side, one channel of each pair being disposed in front of the other, and a series of cards mounted in the frame in overlapped spaced relation, each card having a pair of laterally projecting members adjacent its lower edge extending into one pair of opposed channels, and a pair of laterally projecting members adjacent its upper edge extending into the other pair of opposed channels.

2. An index comprising a frame having two parallel inwardly facing channels at each side, one channel of each pair being disposed in front of the other, and a series of cards mounted in the frame in overlapped spaced relation, each card having a pair of laterally projecting members adjacent its lower edge extending into the inner pair of opposed channels, and a pair of laterally pro-

jecting members adjacent its upper edge extending into the outer pair of opposed channels.

3. An index comprising a frame having two parallel inwardly facing channels at each side, one channel of each pair being disposed in front of the other, and the outer wall of the front channel being narrower than the dividing wall between the two channels, and a series of cards mounted in the frame in overlapped spaced relation, each card having a pair of laterally projecting members adjacent its lower edge extending into one pair of opposed channels, and a pair of laterally projecting members adjacent its upper edge extending into the other pair of opposed channels.

4. In combination with an index card having elements extending from the upper and lower parts respectively of its lateral edges, an index frame comprising an imperforate rigid back formed from sheet material, and channel-forming means arranged at one side of said back and adjacent to the opposite lateral margins thereof respectively, said means being constructed and arranged to provide two parallel inwardly facing channels, one in front of the other, at either margin of the frame for the reception respectively of the upper and lower laterally extending elements of the index card.

5. An index frame comprising a back and two parallel inwardly extending flanges at each side, one in front of the other, forming two pairs of opposed channels, the outer flanges being narrower than the inner flanges.

6. In combination with an index card having elements extending from the upper and lower parts respectively of its lateral edges, an index frame comprising a back, and a pair of inwardly directed flanges arranged at one side of said back and adjacent to each of the lateral margins thereof respectively, one flange of each pair being spaced in front of the other, the rear flanges of each pair being integral with the back, said flanges with the marginal portions of the back being constructed and arranged to form two pairs of opposed channels extending lengthwise of the frame for the reception respectively of the upper and lower laterally extending elements of the index card.

7. An index frame comprising a back and inwardly extending side flanges forming a pair of opposed channels extending lengthwise of the frame, and a channel strip secured adjacent to each side of the frame with its rear flange lying against the frame back and its front flange forming a second channel alongside and parallel to the side flange of the frame.

8. An index frame comprising a back and

- inwardly extending side flanges forming a pair of opposed channels extending lengthwise of the frame, and an angle strip secured to each side of the frame having an inwardly extending flange spaced from the side flange of the frame and forming therewith a second channel alongside and parallel to the first named channel.
9. An index frame comprising a back and inwardly extending side flanges forming a pair of opposed channels extending length-
- wise of the frame, and a channel strip secured over each of said side flanges, the rear flange of the channel strip being attached to the rear side of the frame back and the front flange of the channel strip extending inwardly in front of the frame flange and forming therewith a second channel. 15

Signed by me at Boston, Massachusetts, this ninth day of June, 1921.

JAMES H. RAND.
